UNITED STATES PATENT OFFICE.

GEORGE L. GRIFFITH, OF NEW YORK, N. Y.

INTERNAL-COMBUSTION MOTOR.

1,131,369.

Specification of Letters Patent.

Patented Mar. 9, 1915.

Application filed July 13, 1908, Serial No. 443,223. Renewed February 3, 1915. Serial No. 5,973.

To all whom it may concern:

Be it known that I, GEORGE L. GRIFFITH, a citizen of the United States, residing at New York, in the county of New York and 5 State of New York, have invented certain new and useful Improvements in Internal-Combustion Motors, of which the following is a specification.

My invention relates to engines or motors 10 and particularly of the internal combustion type. Any combustible mixture may be used, such as air with gas, oil or alcohol.

There are today two general types of internal combustion engines known as the two 15 cycle and the four cycle types. Each has its own advantages. For a given size of cylinder more power can be developed in a two cycle operation than in a four cycle. The construction of the two cycle motor is also 20 more simple in some respects. It has been customary however, in the two cycle motor to utilize the crank casing as a compression chamber and this introduces other difficulties and losses. It is my desire to prevent 25 such losses and overcome the difficulties inherent in the usual two cycle motor and also provide a maximum propulsion effort for a given weight of motor.

The preferred method of carrying out the 30 invention will be found more fully described hereinafter and illustrated in the accompanying four sheets of drawings.

The simplest construction which I have 35 thus far perfected for the purpose of the invention comprises a cylinder with a compression chamber at one end and an explosion chamber at the other end and a piston, working in the cylinder. The explosive mixture is drawn into the compression 40 chamber through a puppet valve by suction. The lower cylinder head is supported inside the piston and the ports in the piston and cylinder register at the lower end of the stroke to permit the compressed charge to 45 pass to the explosion chamber. Preferably a puppet valve prevents back flow of the charge. Into the explosion chamber the compressed mixture rushes and drives out the products of combustion of the previous 50 charge. As the piston rises, the exhaust port is closed and the charge is again compressed. At the top of the stroke ignition takes place. One working stroke thus occurs at each revolution of the crank shaft.

55 Any number of cylinders may be used. The invention is in fact especially adapted

for two and four cylinder constructions. Its compactness and the absence of valve mechanism facilitates arrangements for cooling. The ignition mechanism may be of any suitable type which may be regulated and controlled as desired. So also any method of lubrication and of carbureting may be employed.

Figure 1 is a side elevation and partial section of a four cylinder motor embodying the improvements of my invention. Fig. 2 is a vertical section of a single cylinder taken on a plane at right angles to the section of Fig. 1, the piston being in about the middle of its stroke. Fig. 3 is a similar fragmentary section, the piston being at the top of the stroke at the time of ignition. Fig. 4 is a similar fragmentary section, the piston being at the bottom of its stroke at the time of admission and exhaust. Fig. 5 is a side view of the lower cylinder head removed. Fig. 6 is a horizontal section on the plane of the line X X Fig. 2, the piston being down and showing the ports through the piston and cylinder.

The construction shown in Fig. 1 is a four cylinder motor, the cylinders 1, 2, 3 and 4 being arranged in pairs mounted on the frame 5 which forms the crank casing. The crank shaft 6 and the connecting rods such as 7 and 8 are of the usual construction. Any system of cooling may be used as for instance water jackets such as 9.

The cylinder or cylinders are removably 30 mounted on the frame so that pistons can be readily installed or removed. Each piston 10, is hollow and has a ring 11 at the lower end which carries the connecting pin 12. The piston head 13 is thus reciprocated between the upper cylinder head 14 and the lower cylinder head 15. The lower cylinder head 15 is supported by a rod or rods such as 16 and 17 which are carried by lugs 18 and 19 which project from the frame.

The mixture of gas and air is admitted to the chamber 20 beneath the piston head through the valve 21 and supply pipe 22 when the piston is on the up stroke. On the down stroke the mixture is compressed in 105 chamber 20 until the port 23 in the piston wall registers with the port 24 in the cylinder wall. The compressed charge then rushes past the valve 25, through the passage 26 and the port 27 at the top of the cylinder 110 into the combustion chamber 28. At this instant the piston is down and the exhaust

port 29 is open so that the inrushing charge drives the spent gases from the last explosion out of the chamber 28. On the next up stroke the charge is again compressed in chamber 28. At the proper moment at or near the top of the stroke the charge is ignited by a suitable device such as igniter 30.

It should be understood that the type of valves such as 21 and 25 is unimportant.

- 10 The transfer of the compressed mixture through the ports 23 and 24 is controlled solely by the piston. So also the exhaust through port 29 depends only on the piston. The inside and outside of the piston are both
- 15 finished and packing provided as at 31 and 32 of a suitable type so as to afford a good fit without undue friction. Preferably the transfer port 23 is a short distance below the head 13 and the lower cylinder head is cut
- 20 away as at 33 so as to permit a compact arrangement of the parts. By the ordinary method of circuit breaker control the spark can be shifted so that the motor may be run in either direction at will and no reversing
- 25 transmission gear is necessary on a multiple cylinder motor.

The size of the lower compression chamber 20 may be varied for instance by using longer or shorter rods in place of rods 16 and 17 and thus raising or lowering the lower cylinder head 15 so as to change the compression and increase or diminish the power developed.

I wish it understood that the drawings are illustrative only and that the exact proportions and arrangements shown are not essential to the spirit of my invention, the scope of which I have set forth in the claim.

The effect of the method of compression 40 is that the engine runs smoothly and there being no cams or exposed valve mechanism the noisy pounding of the four cycle engine

is dispensed with and greater efficiency than with the ordinary two cycle type is obtained. For an engine of the same bore and stroke 45 my invention develops greater power than either an ordinary two or four cycle engine.

The construction is simple so that the cost is very low. It is particularly adapted to motor vehicles such as cars and boats. A 50 four cylinder motor of my invention equals an eight cylinder motor of the four cycle type in power and runs more quietly. No mechanically actuated valves are necessary and hence what is ordinarily a source of in- 55 creasing annoyance is eliminated.

What I claim is:

A two cycle internal combustion engine comprising an engine cylinder closed at one end, a hollow piston within the cylinder, a 60 fixed head in the cylinder disposed beneath the head of the piston and co-operating with the inside wall of the piston to form a compression chamber inside the piston, a fuel supply pipe extending up inside the cylinder 65 and piston and connected with the internal cylinder head, a valve carried by the internal cylinder head and opening into the compression chamber to admit fuel thereto, the cylinder having a transfer passage ex- 70 tending from the compression chamber beneath the piston into the upper portion of the cylinder above the piston therein, a valve arranged to prevent reverse flow through the transfer passage back to the 75 compression chamber, and the piston having a port therein arranged to register with the transfer passage in the cylinder whereby to provide communication between the compression chamber and the transfer passage. 80

GEORGE L. GRIFFITH.
